UNITED STATES PATENT OFFICE.

WILLIAM C. GLASS, OF ROSLINDALE, MASSACHUSETTS, ASSIGNOR TO UNITED PRINTING MACHINERY COMPANY, OF BOSTON, MASSACHUSETTS, A CORPORATION OF MAINE.

GRIPPING DEVICE.

1,139,760.

Specification of Letters Patent. Patented May 18, 1915.

Original application filed November 8, 1912, Serial No. 730,165. Divided and this application filed October 23, 1913. Serial No. 798,965.

To all whom it may concern:

Be it known that I, WILLIAM C. GLASS, a citizen of the United States, and a resident of Roslindale, in the county of Suffolk and State of Massachusetts, have invented an Improvement in Gripping Devices, of which the following description, in connection with the accompanying drawings, is a specification, like characters on the drawings representing like parts.

This invention relates to gripping devices, and more especially, though not necessarily exclusively, to grippers for sheet feeding mechanisms for presses. It is more particularly applicable to presses of the bed and swinging platen type, but is not limited in its application thereto, as it is also capable of being applied to other types of presses, as, for example, presses of the cylinder type.

20 This application is a division of my prior pending application, Serial No. 730,165.

My invention will be best understood by reference to the following specification, when taken in connection with the accompanying drawings of one specific embodiment thereof, while its scope will be more particularly pointed out in the appended claims.

In the drawings: Figure 1 is a plan of one form of gripper mechanism embodying my invention, certain parts of which are shown partly broken away; Fig. 2 is a sectional view on line 2—2 of Fig. 1; Fig. 3 is a detail sectional view, partly broken away and shown on an enlarged scale, on line 3—3 of Fig. 1; Fig. 4 is a detail sectional view on line 4—4 of Fig. 1; and Fig. 5 is a sectional view on line 5—5 of Fig. 2.

Referring to the drawings, and to the embodiment of my invention which I have selected for illustration, I have there shown a gripper mechanism comprising a carrier which may be of any other appropriate character, and otherwise suitably mounted, but herein consisting of a frame intended to have a reciprocatory motion imparted thereto by a mechanism which it will be unnecessary here to describe. This mechanism will, by preference, impart a forward motion to the carrier so that the grippers carried thereby will receive and grasp the sheet, and a backward motion to cause the sheet to be carried from one point to another and then released. The present invention, how-

ever, is concerned merely with the carrier, grippers, and gripper operating mechanism.

Mounted in guideways 10 in a side frame member 11, and in guideways 12 in a side frame member 13, are two slides 14 and 15, rigidly connected to each other by rods 16 and 17. This structure constitutes a sliding carrier for the grippers presently to be described. Preferably, the slide 14 is provided with shoulders 18 arranged in sliding contact with a finished face 19 of the side frame member 11, to hold the slide against lateral movement in one direction, while the slide is provided with a groove 20 which receives a key 21 secured to the frame member 11, to hold the slide against lateral movement in an opposite direction. At the other side of the machine, the slide 15 is preferably without lateral guides, so that the side frame is free to come and go somewhat, without affecting the position of the slides 14 and 15.

Mounted in the slides 14 and 15, is a rock shaft 22, the chief purpose of which will be explained presently. Mounted upon the rock shaft 22, and upon the fixed rod 17, is a gripper support 23. In practice, two or more of these gripper supports, with their attached parts, will usually be employed, but, since they will be substantial duplicates of each other, it is deemed necessary herein to show but one. The gripper support is herein forged to provide a pair of arms 24, between which is located an arm 25 secured to the rock shaft 22, by means of a key 26 and a clamping screw 27 passing through and threaded into a split ear 28. Mounted on the gripper support 23 is a gripper 29, which is fixed in the operation of the machine, but preferably capable of lengthwise adjustment, it being provided for this purpose with a dovetailed groove 30, which receives a correspondingly dovetailed guide 31 on the gripper support. As a means for adjusting the gripper longitudinally, it may be provided with a transverse slot 32, having therein the head of an eccentric stud 33, provided with a shank 34, swiveled in the gripper support 23. The eccentric stud may be provided with a slot 35 to receive a screwdriver, by means of which it may be conveniently rotated to advance or retract the gripper. By longitudinally adjusting the gripper, the

point against which the edge of the sheet abuts may be varied to suit the requirements. The gripper may be secured in the desired position of adjustment by a clamping screw 36 passing through a longitudinal slot 37 provided in the gripper, said screw being threaded into the gripper support 23. The gripper 29 is provided at its forward end with laterally extending sheet gripping surfaces 38, preferably having a slight downward inclination toward their extremities to facilitate the entrance of the edge of the sheet. Coöoperating with these fixed gripping surfaces are two movable grippers 39 having sheet engaging surfaces 40, preferably having a downward inclination corresponding to that of the surfaces 38. These movable grippers are preferably mounted on a pivot 41 on the gripper support 23, and said grippers are connected to each other by a pin 42.

A bell crank lever 43, secured to a rock shaft 44 mounted in bearings in the gripper support 23, is provided with a forked arm 45, which receives the pin 42. The bell crank lever is provided with a pair of arms 46, pivoted at 47 to a collar 48 interposed between said arms. The collar 48 is secured to a rod 49, arranged to slide through a sleeve 50 pivoted at 51 to the arm 25, the latter for that purpose being forked to straddle the sleeve 50. A spring 52 encircling the rod 49 bears at one end against the sleeve 50, and at its other end against a nut 53, threaded onto the rod, and serving as a means of adjustment for the spring. A lock-nut 54 may be provided to secure the nut 53 in the desired position of adjustment.

As a means for rocking the shaft 22 to 40 actuate the movable gripper 39, said rock shaft has secured thereto an arm 55, having journaled thereon a cam roll 56 located in the cam path of a stationary cam 57, secured to the side frame member 13. By giving the 45 cam path the proper shape, it may be caused to utilize a forward and backward movement of the slides 14 and 15, and the described mechanism carried thereby, to open and close the grippers. To this end, the 50 cam is provided with two straight portions 58 and 59, and two depressed portions 60 and 61, the latter being shallower than the former. When the slides 14 and 15, and the mechanism carried thereby, are in their 55 retracted position shown in Figs. 2 and 4, the grippers are open. When, however, the slides and mechanism carried thereby start to advance, the cam roll 56 rises into the straight elevated portion 58 of the cam path, 60 thus acting through the arm 55, rock shaft 22, arm 25, and sleeve 50, to place the spring 52 under tension, and apply spring pressure to close the grippers 39 upon the sheet, thus gripping the latter firmly against the grippers 29. The depth of the depression 65

is only sufficient to cause the spring pressure of the grippers upon the sheet to diminish at that point, without entirely removing the pressure, and hence there is no danger of the grippers dropping the sheet 70 during their forward movement. In some cases, where the grippers are used in connection with mechanism for feeding box or carton blanks, and where the latter are to be cut, it is desirable to have the cut extend clear to the other edge of the sheet, and since the sheet is to be held in the press by the grippers during the cutting and creasing operation, it is necessary to provide the grippers 29 with a notch 62, to permit the 80 sheet to be cut clear up to its front edge, without interference with the grippers. 75

As already stated, the carrier may be given a forward and backward motion by any appropriate mechanism, which it will be unnecessary here to describe, since it forms no essential part of my present invention. It will be understood, however, that the cam 57 is adapted to operate the lever or arm 25 positively for both opening 90 and closing the grippers 29 and 39, and that the spring 52 is adapted to be moved bodily by the operative movement of said lever, and is adapted to cause said grippers to close upon the complete closing movement of said 95 lever. It will also be observed that, during the opposite movement of the lever, the spring pressure is first removed, after which the grippers are positively opened to release the sheet. 100

While I have herein shown and described one specific embodiment of my invention for illustrative purposes, and have disclosed and discussed in detail the construction and arrangement incidental to one specific application thereof, it is to be understood that the invention is limited neither to the mere details or relative arrangement of parts, nor to its specific embodiment herein shown, but that extensive deviations from the illustrated form or embodiment of the invention may be made, without departing from the principles thereof. 105

Having thus described my invention, what I claim, and desire by Letters Patent to 110 procure, is:

1. The combination of a carrier, a plurality of grippers mounted thereon, a lever connected with said grippers, by a stroke of which lever said grippers are operated, and cam-mechanism adapted to operate said lever positively for both opening and closing said grippers, the connections between said grippers and said lever comprising a spring adapted to cause said grippers to close upon the complete closing movement of said lever. 120

2. The combination of a carrier, a plurality of grippers mounted thereon, a lever connected with said grippers, by a stroke of 125

- which lever said grippers are operated, and cam-mechanism adapted to operate said lever positively for both opening and closing said grippers, the connections between 5 said grippers and said lever comprising a spring adapted to be moved bodily by the operative movement of said lever and adapted to cause said grippers to close upon the complete closing movement of said lever.
- 10 3. The combination of a carrier, a plurality of grippers mounted thereon, an actuating member connected with said grippers, by a stroke of which member said grippers are operated, and mechanism adapted positively 15 to operate said member for both opening and closing said grippers, the connections between said grippers and said member comprising yielding means adapted to cause said grippers to close upon the complete closing movement of said member.
- 20 4. The combination of a carrier, a plurality of grippers mounted thereon, an actuating member connected with said grippers, by a stroke of which member said grippers are operated, and mechanism adapted positively 25 to operate said member for both opening and closing said grippers, the connections between said grippers and said member comprising yielding means adapted to be moved bodily by the operative movement 30 of said member and adapted to cause said grippers to close upon the complete closing movement of said member.
- 35 5. The combination of a carrier, a plurality of grippers mounted thereon, an actuating member connected with said grippers, by a stroke of which member said grippers are operated, and mechanism adapted to operate 40 said member for both opening and closing said grippers, said mechanism comprising a positively acting fixed travel actuator, and the connections between said actuator and said grippers comprising yielding means adapted to cause said grippers to close upon complete closing movement of 45 said member.
- 50 6. The combination of a carrier, a plurality of grippers mounted thereon, an actuating member connected with said grippers by a stroke of which member said grippers are operated, means for imparting a positive to and fro movement to said member, and yielding means interposed between said member and one of said grippers whereby the latter are closed with yielding pressure. 55
- 60 7. The combination of a carrier, gripping means mounted thereon, a rockshaft mounted on said carrier and connected to said gripping means positively to open the same, means to impart a positive rocking motion to said rockshaft, and yielding means interposed between said rockshaft and said gripping means whereby the latter is closed with yielding pressure and opened positively. 65
- 70 8. The combination of a carrier, gripping means mounted thereon, an actuator mounted on said carrier, and connected to said gripping means positively to open the same, means to impart a positive to and fro motion to said actuator, and yielding means interposed between said actuator and said gripping means whereby the latter is closed with yielding pressure and opened positively. 75

In testimony whereof, I have signed my name to this specification, in the presence of two subscribing witnesses.
